UNITED STATES PATENT OFFICE.

CARL C. PETERSON, OF WASHINGTON, DISTRICT OF COLUMBIA.

HOSE-SUPPORTER.

1,815,573.

Specification of Letters Patent.

Patented Sept. 9, 1919.

Application filed January 10, 1919. Serial No. 270,531.

To all whom it may concern:

Be it known that I, CARL C. PETERSON, a citizen of the United States, residing at Washington, in the District of Columbia, have invented certain new and useful Improvements in Hose-Supporters, of which the following is a specification.

This invention relates to hose supporters and has for its object the provision of a comparatively simple and thoroughly efficient device of this character, the construction of which is such that when the supporting band loses its elasticity or otherwise becomes impaired from continued use, said band may be readily detached from the clasp suspension element and replaced by a new band, thus permitting repeated use of the suspension element and clasp and consequently prolonging the effective life of the supporter.

The invention further contemplates the provision of a hose supporter, the suspension element of which is formed with a pocket adapted to receive the supporting band, the parts being provided with interengaging fastening devices so that by releasing said fastening devices the band may be quickly withdrawn from the pocket and replaced by a new band when necessary.

The invention further aims to provide a novel form of garment-engaging clasp including a stationary member having a circumferential seating groove and a pivoted member coacting therewith and adapted to clamp the hose within said groove when the free end of the pivoted member is swung downwardly to operative position.

A further object is to provide novel means for detachably connecting the ends of the supporting band and means disposed at the rear of the garment-engaging clasp for preventing the latter from coming in direct contact with the leg of the wearer.

A still further object of the invention is generally to improve this class of devices so as to increase their utility, durability and efficiency.

Other and incidental objects will appear as the description proceeds. In the drawings wherein I have illustrated the preferred embodiment of the invention, and wherein similar reference characters designate corresponding parts throughout the several views:

Figure 1 is a perspective view of a gar-

ment supporter embodying the present invention showing the application of the same;

Fig. 2 is a front elevation of the garment-engaging clasp detached;

Fig. 3 is a transverse sectional view taken on the line 3—3 of Fig. 2 and looking in the direction of the arrows;

Fig. 4 is a perspective view of portions of the supporting band and suspension element detached showing the construction of the interengaging fastening devices;

Fig. 5 is a side elevation partly in section showing the pivoted clamping bail about to engage the upper edge of the hose;

Fig. 6 is a vertical sectional view taken on the line 6—6 of Fig. 1.

Corresponding and like parts are referred to in the following description and indicated in all the views of the drawings by the same reference characters.

The improved hose supporter forming the subject-matter of the present invention comprises an elastic supporting band 5 adapted to encircle the leg of the wearer and to which is detachably secured a clasp suspension element or pad 6. The suspension element 6 is preferably substantially triangular in shape, as shown, and secured to the upper edge thereof is a strip of material 7 folded upon itself and stitched or otherwise secured to the pad 6, as indicated at 8, to form a segmental pocket 9 adapted to receive the supporting band 5.

The suspension element 6 is detachably secured to the supporting band 5 by interengaging fastening devices 10 and 11, the fastening devices 10 being preferably in the form of substantially circular heads secured to the supporting band 5 at predetermined points in the length thereof and the fastening devices 11 being preferably in the form of resilient sockets secured to one of the walls of the pocket 9 and adapted to receive the heads 10.

By arranging the parts in this manner when the supporting band 5 loses its elasticity or otherwise becomes impaired from continued use, the same may be readily withdrawn from the pocket 9 and replaced by a new supporting band by merely disengaging the fastening devices 10 and 11 as will be readily understood.

Depending from the lower or reduced end of the suspension element 6 is a plate 12 con-

- stituting one element of a garment-engaging clasp, the other element of the clasp being in the form of a bail 13, the upper end of which is pivotally mounted in suitable eyes 14 arranged on the outer face of the plate 12, as best shown in Fig. 5 of the drawings. The upper end of the plate 12 is provided with an opening 15 through which extends the reduced end of the suspension element or pad 6, the pad being secured to the plate 12 by stitching or otherwise as desired. Projecting laterally from the outer face of the plate 12 is an enlargement 16 having its peripheral edge formed with a concave seating groove 17 adapted to receive the material of which the hose is formed when the clamping member or bail 13 is swung downwardly to lowered position. The lower end of the projection 16 is preferably curved or rounded while the free end of the clamping bail 13 is correspondingly curved or rounded so as to conform to and fit within the seating groove 17. The plate 12 at the lower or curved portion of the projection 16 is preferably cut away at 18 in order to lighten the same and arranged directly above said cut-away portion is a transverse reinforcing web 19 which connects the adjacent side walls of the projection 16 and serves to prevent spreading of the walls thereof. Arranged at the rear of the plate 12 is a backing strip 20 so as to prevent the clasp from coming in direct contact with the leg of the wearer. The plate 12 is formed with a plurality of laterally extending attaching eyes 21 and the backing 20 is preferably secured to the plate by stitching the eyes 21 thereto, as best shown in Fig. 2 of the drawings. Projecting longitudinally from the free end of the clamping bail is a finger piece 22, by means of which the said bail may be conveniently released from engagement with the garment when it is desired to release the hose.
- It will thus be seen that by positioning the upper edge of the hose over the projection 16 and swinging the free end of the clamping bail 13 downwardly, the material at the upper edge of the hose will be forced within the seating groove 17 and in which position it will be securely clamped by engagement with the bail 13 which, as shown in Fig. 3 of the drawings, also enters the seating groove 17.
- In order to provide for the ready connection and disconnection of the ends of the supporting band 5, I provide a novel form of fastening including coacting members, one of which is in the form of a plate 23 having a substantially V-shaped projection 24 stamped or otherwise formed integral therewith and having its opposite inclined walls grooved at 25. The plate 23 is provided with laterally extending loops 26 which bear against the supporting band 5 and to which they are secured by one or more stitches. Secured to the other end of the supporting band 5 is a fastening device 27, preferably formed of a single length of wire, the forward end of which is bent to 70 form a substantially triangular loop 28 adapted to fit over the projection 24 and into the groove 25 thereof, the walls of the loop 28 being preferably resilient so as to permit slight lateral expansion and 75 contraction thereof to accommodate the portion 24. When the ends of the supporting band 5 are drawn together and the loop 28 is positioned over the projection 24 and a slight longitudinal pull 80 exerted on the member 27, the loop 28 will frictionally engage the grooved walls of the projection 24 and thereby prevent accidental separation of the ends of the supporting band. The supporting band is 85 passed through the attaching loop of the fastening device 27 and the end of said band extended through a buckle 27' of any suitable construction so as to permit the band to be adjusted to fit the leg of the wearer. 90
- Inasmuch as the suspension element or pad 6 carrying the garment-engaging clamp is detachably secured to the supporting band 5, the suspension element and garment-engaging clasp may be used over and over 95 again by merely substituting a new supporting band for the worn or impaired one thus materially prolonging the effective life of the hose supporter. It will, of course, be understood that the hose supporters may be made in different sizes and shapes and that any desired type of fastening devices may be employed for detachably securing the suspension element to the supporting band without departing from the spirit of 100 the invention.
- Having thus described the invention, what is claimed as new is:
1. A hose supporter including a supporting band, a clasp suspension element having a pocket formed therein for the reception of the band, and interengaging fastening devices carried by said band and the wall of the pocket. 110
  2. A hose supporter including a supporting band, a clasp suspension element, a strip of material secured to the upper portion of the suspension element and folded to form a pocket adapted to receive a portion of the supporting band, and interengaging fastening devices carried by said pocket and supporting band for detachably securing the suspension element in position on the supporting band. 115
  3. A hose supporter including a supporting band having interengaging ends, a clasp suspension element having a pocket adapted to receive a portion of the band, spaced heads secured to the supporting band, and resilient sockets secured to one wall of the 120
  4. A hose supporter including a supporting band having interengaging ends, a clasp suspension element having a pocket adapted to receive a portion of the band, spaced heads secured to the supporting band, and resilient sockets secured to one wall of the 125
  5. A hose supporter including a supporting band having interengaging ends, a clasp suspension element having a pocket adapted to receive a portion of the band, spaced heads secured to the supporting band, and resilient sockets secured to one wall of the 130

socket and adapted to receive the heads for detachably securing the suspension element in position on the supporting band.

4. A hose supporter including a supporting band having interengaging ends, a clasp suspension element having a pocket adapted to receive a portion of the band, and a fastening device including coacting members

one of which is secured to the band and the other to the pocket for detachably securing the suspension element in position on the supporting band. 10

In testimony whereof I affix my signature.

CARL C PETERSON. [L. s.]
